UNITED STATES PATENT OFFICE.

ARTHUR COOPER, OF EARLSBORO, OKLAHOMA.

LUBRICATING DEVICE FOR STEAM ENGINES.

Application filed September 17, 1926. Serial No. 136,156.

This invention relates to lubricating devices for steam engines and has for its principal object the provision of means for introducing oil by means of boiler pressure into the steam line from the boiler to engine against the pressure in said steam line.

This makes necessary the provision of step-up means for imparting to the oil a pressure superior to boiler pressure, and the 10 present invention, in its more specific concept relates to the provision of pressure differentiating means, actuated by boiler pressure, and in turn transmitting a greater pressure to a body of oil which also is in communication with the steam line.

Other objects of the invention will appear as the following description of a preferred embodiment thereof proceeds.

In the drawings, 20 Fig. 1 is a vertical section, more or less diagrammatic in form, showing one embodiment of my invention.

Fig. 2 is a similar view showing a slightly modified form of the invention. 25 Referring now in detail to the several figures, and first advertiring to that form of the invention shown in Fig. 1, the reference numeral 1 represents a cylinder in which a piston 2 is reciprocably mounted, said piston 30 separating the cylinder into upper and lower chambers. The former of which, designated by the reference character 3 is the oil reservoir having the piston 2 for its bottom, while the lower chamber 4 is a water space, the 35 water being the condensate of steam admitted slowly through the pipe 5, the latter being in communication with the steam line 6 which conveys the working pressure of the boiler to the engine.

The oil chamber 3 is also in communication with the steam line by means of the pipe 7.

It is obvious that pressure from the steam line is in communication with the cylinder 45 on both sides of the piston 2, which ordinarily would render the piston entirely inert. But in the present instance the principle of the differential pistons is employed, a displacement plunger 6 being secured to the 50 piston 2 and extending through the upper head of the cylinder through the stuffing gland 9.

The object of the displacement plunger is to reduce the area of the upper face of the 55 piston 2 exposed to pressure of the oil in the oil chamber. Since the same pressure per

square inch is admitted to both sides of the piston 2, and since the area of the lower face of the piston exceeds that of the annular upper face, it follows that there will be an 60 aggregate pressure against the lower face greater than that against the upper face, said greater pressure being transmitted through the piston to the body of oil in the oil chamber increasing the pressure per 65 square inch upon the oil.

For instance, a boiler pressure of 100 lbs. transmitted through the pipe 5 to the water in the cylinder below the piston 2 is increased, perhaps 105 lbs. per square inch on the upper face of the piston 2, the water acting as a liquid piston. This pressure is transmitted to the oil as the piston rises, forcing it at a pressure superior to the steam pressure into the steam line 6.

The oil discharge pipe 7 is controlled by a valve 8 through which normally only a very small jet of oil passes, so that the upper movement of the piston 2 is extremely slow, a great many hours being ordinarily required to empty the oil chamber. This gives ample time for the steam entering the pipe 5 to condense into water to meet the demands of the increasing capacity of the water chamber as the piston rises.

When it is desired to fill the oil chamber it is first necessary that the piston 2 along with the displacement plunger 6 be returned to its original position with the piston 2 at or adjacent the lower end of the cylinder 1. 90 This may be accomplished by shutting the valve 10 in the pipe 5 thus cutting off steam pressure from the lower end of the cylinder, and opening the drain cock 11 to vent the water chamber. The oil controlling valve 12 is left open and steam entering there-through, overbalances the piston 2, returning it to the bottom of the cylinder. The valve 12 is then temporarily closed and the oil chamber vented by opening the funnel valve 13. When the pressure in the oil chamber has become sufficiently reduced the oil may then be replenished through the funnel, after which the several valves may be adjusted to restore the device to normal 95 operative condition.

In that form of my invention shown in Fig. 2, a cylinder 14 of two diameters is provided, the lower part 15 which is of larger diameter being in communication with the steam line, by means of the steam pipe 16, and the upper part 17 of smaller

diameter being in communication by means of the oil pipe 18 with said steam line.

A piston 19 is mounted for reciprocation within said cylinder, said piston having an 5 enlarged lower head fitting that part of the cylinder which is of larger diameter and a relatively small upper head 21 fitting that part of the cylinder which is of smaller diameter. The piston is of such height as to 10 form a chamber in the part of the cylinder of smaller diameter when the piston is at the lower end of its stroke, this chamber being an oil reservoir which may be filled, upon depletion of the oil contained therein, by 15 means of the valve controlled funnel 23. The trunk of the piston 19 is of uniform diameter between the two heads leaving an annular space 24 surrounding it within the 20 lower part of the cylinder, said space being capable of being put into communication 25 with the steam line by means of the valve controlled pipe 25. Said annular space may be vented when necessary through a valve controlled passage 28. The oil discharge 30 pipe 18 is also valve controlled and formed with a sight glass 26 by means of which the rate of operation of the lubricating device may be ascertained in the usual manner. A valve controlled drain pipe 27 is tapped into the lower head of the cylinder.

The piston operates upon the principle of differential pressures, the outer face of the enlarged head 20 being of greater area than that of the head 21 so that equal pressure per unit of area acting upon the outer 35 faces of said piston heads will produce an excess aggregate pressure upon the outer face of the piston head 20, forcing the piston upwardly against the body of oil in the 40 reservoir 22. Since the steam pressure from the steam line acts with equal pressure upon the lower head of the piston through the pipe 16 and upon the body of oil in the reservoir through the pipe 18, it is the slight 45 excess pressure produced by the differences in area of the two heads of the pistons which is relied upon to force oil through the valved discharge pipe 18 into the steam line.

It will be understood that ordinarily the 50 opening through the pipe 18 will be exceedingly restricted, its passage at any time being controlled by the valve 27 so that the rise of the piston 19 will be extremely slow. When the reservoir has finally been emptied 55 and it is desired to recharge it, it becomes necessary as in the first described apparatus to cause the piston to return to its original position at the bottom of the cylinder. This

is accomplished by cutting off the valve in the steam pipe 16 opening the valve in the 60 drain pipe 27 so as to vent the cylinder chamber below the piston head 20. The valve in the steam pipe 25 is then turned on admitting steam under boiler pressure to the annular part 28 of the piston head 20 65 surrounding the trunk of the piston. The area of the piston head 21 plus the area of the annular part of the piston head 20, equals the area of the lower face of the piston head 20. It is obvious therefore that any 70 steam pressure whatsoever entering the annular space surrounding the piston trunk is sufficient under the conditions described to return the piston to its normal position. When the upper part of the cylinder has 75 been vacated by the piston the funnel may be opened and a fresh supply of oil poured in.

Although I have disclosed what I believe to be practical and preferred forms of my 80 invention, yet it is to be understood that the description is not to be considered limitative in its relation to the invention, but merely exemplary of one way in which the 85 invention may be carried out.

I claim:

Means for introducing lubricating oil into the steam supply of a steam engine, comprising a casing of two diameters and a piston of two diameters working therein, the 90 part of said casing of smaller diameter and the corresponding part of said piston together forming a reservoir having a movable bottom wall and the part of said casing of larger diameter forming with said piston 95 an annular chamber having a movable bottom wall, means for placing said reservoir into communication with the steam supply, valve controlled means for subjecting the end of larger diameter of said piston to the 100 pressure of the steam supply and valve controlled means for placing said annular chamber into communication with the steam supply to permit selectively counterbalancing the normally predominant steam pressure 105 on that part of the piston of larger diameter by admitting steam simultaneously to said reservoir and annular chamber for stopping the flow of lubricant to said system and for reversing the direction of travel of said piston for filling said reservoir by cutting off the steam pressure from the part of the piston of larger diameter.

In testimony whereof I affix my signature.

ARTHUR COOPER.
